FLOWER VASE OR SIMILAR ARTICLE

Nathan W. Roop, Columbus, Ohio, assignor to Columbus Plastic Products Inc., Columbus, Ohio, a corporation of Ohio

Filed Apr. 23, 1962, Ser. No. 69,819

Term of patent 14 years

(Cl. D29—28)

FIG. 1 is a perspective view of a flower vase or similar article, showing my new design;

FIG. 2 is a side elevational view on a slightly larger scale; and

FIG. 3 is a bottom plan view thereof.

The side of the flower vase or similar article not shown in the drawing is identical to that shown in FIGS. 1 and 2.

I claim:

The ornamental design for a flower vase or similar article, substantially as shown and described.
